his Attorney.

UNITED STATES PATENT OFFICE.

CARL O. ERICKSON, OF ST. PAUL, MINNESOTA.

PREHEATING DEVICE.

Application filed January 23, 1922. Serial No. 531,140.

To all whom it may concern:

Be it known that I, CARL O. ERICKSON, a citizen of the United States, residing at St. Paul, in the county of Ramsey and State of Minnesota, have invented certain new and useful Improvements in Preheating Devices, of which the following is a specification.

My invention relates to means for pre-heating the gas mixture passing into the cylinders of an internal combustion engine from an attached carburetor, its object being, particularly, to provide a simple and improved electrically energized heating unit to be disposed between the carburetor and manifold, co-operating means in connection with the pre-heating element being provided for breaking up the gas mixture and consisting in the efficiency of the heating element.

To this end my invention consists in the features of construction and combination hereinafter more particularly described and claimed:

Referring to the drawings, forming part of the specification,

Figure 1, shows my device in elevation.

Fig. 2, is a central vertical longitudinal sectional view of same partly broken away, and

Fig. 3, shows my device raised in position for use with the containing parts partly broken away.

Referring to the drawings, A represents a supporting plate for my device adapted to be secured between the flanges 2 and 3, formed respectively upon the ends of the carburetor outlet pipe 4, and the manifold inlet pipe 5, the plate A being formed with openings 6 through which openings and the openings 7 in the flanges, the ordinary securing belts may be passed. Arranged beneath the plate A is the plate B centrally supporting a spiral coil 8, the base of the spiral coil extending through insulation 9 fitted in an opening in the plate A. The upper end of the spiral coil is anchored to the overhanging top of a bracket 10 supported upon the plate A.

Rotatably supported between the plate A and the overhanging top of the bracket 10 and surrounding the coil 8, is a mixing device made up of a plurality of blades 11 connected at their upper ends to a plate 12 and at their lower ends to a plate 13. The

upper end of the spiral coil constitutes a bearing for the plate 12 and the insulation 9 around the base of the spiral constitutes a bearing for the supporting plate 13 of the mixer.

The under plate B carries a conducting arm 14 to be connected to a source of electrical energy, not shown. The plates A and B are formed with openings 15 upon opposite sides of the center bar 16, through which the gas mixture will pass from the carburetor.

The device is positioned between the flanges 2 and 3, as shown in Figure 3, with the combined pre-heating coil and mixer projecting into the manifold pipe.

My invention is, particularly, adapted for use in connection with automobile engines to facilitate the starting of the engine, as in cold weather, by pre-heating the vapor mixture and placing it in a condition for prompt explosion through the current ordinarily supplied through the spark plugs.

A particular advantage of my construction is the co-operative relationship of the mixing blades and heating coil. The gas mixture passing, as it does, through the opening 15 will be caught by the blades, causing a mixing of the gas and a circulating of it in that mixed condition around the coil to secure the most efficient heating of the gas mixture.

I claim:

1. In combination with a carburetor outlet and manifold inlet, a perforated plate positioned between the same, an electric heating unit mounted upon said plate and projecting into the manifold inlet and rotatably mounted mixing blades arranged around and extending forwardly alongside said unit.

2. In combination with a carburetor outlet and manifold inlet, a perforated plate secured between the same, an electric conducting coil mounted upon said plate and projecting into the manifold inlet, mixing blades rotatably supported upon said plate and projecting forwardly alongside said coil, and a bracket carried by said plate and overhanging said coil and blades and forming an end support therefor.

In testimony whereof I affix my signature. CARL O. ERICKSON.
